UNITED STATES PATENT OFFICE.

WILLIAM J. ALLIN, OF CLARENDON, ARKANSAS.

RAILROAD-TIE PLATE.

SPECIFICATION forming part of Letters Patent No. 601,766, dated April 5, 1898.

Application filed July 3, 1897. Serial No. 643,407. (No model.)

To all whom it may concern:

Be it known that I, WILLIAM JOHN ALLIN, of Clarendon, in the county of Monroe and State of Arkansas, have invented a new and 5 Improved Railroad-Tie Plate, of which the following is a full, clear, and exact description.

The object of the invention is to provide a new and improved metallic railroad-tie plate which is simple and durable in construction 10 and arranged to properly support a rail and permit of securely fastening the same in place and at the same time prevent the tie-plate from slipping on the tie.

The invention consists principally of a rolled 15 plate formed with a turned-up lip in its body portion for engagement with one side of the base of the rail.

The invention also consists of certain parts 20 and details and combinations of the same, as will be fully described hereinafter and then pointed out in the claim.

Reference is to be had to the accompanying 25 drawings, forming a part of this specification, in which similar characters of reference indicate corresponding parts in all the figures.

Figure 1 is a plan view of the improvement as applied. Fig. 2 is a side elevation of the same. Fig. 3 is a transverse section of the same. Fig. 4 is a perspective view of the improvement, and Fig. 5 is an under side perspective view of the same.

The improved tie-plate A is adapted to rest 30 on a tie B and is formed of rolled iron or steel and is provided in its body portion with a struck-up lip A', curved so as to pass over and engage one side of the base of a rail C, as is plainly illustrated in the drawings. The other side of the base of the rail C is engaged

by one or more spikes D, driven through an aperture A², formed in the plate A, and into 40 the tie B, so that the rail is securely locked in place on the tie-plate.

On the under side of each plate A are formed 45 one or more transverse ribs A³, adapted to embed themselves in the top surface of the tie B, so as to prevent longitudinal as well as lateral movement of the tie-plate on the tie. In using the tie-plates I reverse the said tie-plates alternately on the ties, as is plainly indicated in Fig. 1, so that the lips A' of successive tie-plates are alternately on opposite 50 sides of a rail to engage the base of the rail on both sides.

It is understood that by having the ribs A³ and the spikes D the tie-plates A are securely 55 locked in position on the ties B, and consequently the rails are not liable to spread, as is so frequently the case with tie-plates now in use.

Having thus fully described my invention, 60 I claim as new and desire to secure by Letters Patent—

A railroad-tie plate, consisting of a rectangular plate, having a turned-up lip cut from the body of the plate and designed to engage 65 the base-flange of a rail, an aperture for a spike in alignment with the lip, and two parallel V-shaped ribs located on the reverse side of the plate from the lip, extending from end to end of the plate near the side edges thereof, 75 and adapted to be embedded in the tie lengthwise of the grain, substantially as described.

WILLIAM J. ALLIN.
